UNITED STATES PATENT OFFICE

HENRY GOLDBLATT, OF KANSAS CITY, MISSOURI

PLASTER SCRATCHER

Application filed March 11, 1929. Serial No. 346,189.

My invention relates to plaster scratchers. The object of my invention is to provide a novel plaster scratcher, adapted for use for scratching plaster walls and ceilings, which is simple, cheap, strong, durable, not liable to damage by rough usage, which is light and easy to use, and which is efficient in its operation.

The novel features of my invention are 10 hereinafter fully described and claimed.

In the accompanying drawing, which illustrates the preferred embodiment of my invention,

Fig. 1 is a rear elevation of my improved 15 scratcher, partly broken away.

Fig. 2 is an end elevation of the same.

Fig. 3 is a plan view of the tooth plate.

Fig. 4 is a section on the line 4—4 of Fig. 1.

Similar reference characters designate 20 similar parts in the different views.

1 designates a relatively long transverse body portion having in its forward edge a right angled longitudinal groove 2 in which is mounted a relatively thin plate 3, preferably of spring steel, provided with parallel forwardly extending flexible resilient pointed teeth 4.

The plate 3 is held releasably fastened to the portion 1, in the groove 2, by a clamping 30 member comprising a plate 5 having one or more transverse holes through which extend securing devices comprising, as shown, bolts 6, which also extend through holes 7 in the plate 3, and through the portion 1, the bolts having 35 on them nuts 8 which bear against the portion 1.

A central handle 9 extends rearwardly from the body portion 1 at an acute angle, preferably, to the plane of the teeth 4. By 40 having the handle disposed centrally and at an angle acute to the plane of the teeth, the scratcher is easily held in a position in which the teeth will depress grooves in the plaster without tearing it up.

45 By having the teeth 4 flexible and resilient, if a tooth strikes a hard object, such as a small lump or stone, the tooth will bend and raise from the plaster surface, without disturbing the even travel of the other teeth, and 50 without deflecting the implement as a whole.

In case a tooth or teeth become broken, the plate 3 may be readily removed and another plate substituted therefor.

I do not limit my invention to the structure shown and described, as modifications, within the scope of the appended claim, may be made without departing from the spirit of my invention.

What I claim is:—

A plaster scratcher having a relatively 60 long transverse portion having in one side a groove, a plate mounted in said groove, said plate having forwardly extending relatively widely spaced resilient pointed teeth, a clamping member mounted in said groove 65 and against said plate and holding said plate clamped to one side of said portion, removable securing means extending through said clamping member and said plate and engaging said portion for holding said member 70 clamped to said plate and the latter clamped to said portion, and a central handle extending rearwardly from said portion at an acute angle to the plane of said plate.

In testimony whereof I have signed my 75 name to this specification.

HENRY GOLDBLATT.
